Primary Examiner — Cathron C Brooks*Assistant Examiner* — Aula Soroush(74) *Attorney, Agent, or Firm* — Edell, Shapiro & Finnian, LLC(57) **CLAIM**

The ornamental design for set of traction elements for shoe outsole, as shown and described.

DESCRIPTION

FIG. 1 is a perspective view of set of traction elements for shoe outsole showing my new design;

FIG. 2 is a bottom plan view thereof;

FIG. 3 is a front side view in elevation thereof;

FIG. 4 is a rear side view in elevation thereof;

FIG. 5 is a left side view in elevation thereof;

FIG. 6 is a right side view in elevation thereof; and,

FIG. 7 is a bottom plan view of the set of traction elements for shoe outsole.

The broken line illustration of environmental structure in FIGS. 1-7 is not part of the claimed design.

1 Claim, 5 Drawing Sheets---
